UNITED STATES PATENT OFFICE.

THOMAS C. SPELLING, OF NEW YORK, N. Y.

PULLER FOR STOPPERS.

1,341,680.

Specification of Letters Patent.

Patented June 1, 1920.

Application filed July 12, 1918. Serial No. 244,544.

To all whom it may concern:

Be it known that I, THOMAS C. SPELLING, a citizen of the United States, residing at New York city, in the county of New York and State of New York, have invented certain new and useful Improvements in Pullers and Stoppers, of which the following is a specification.

This invention relates to pullers for stoppers, and has for a purpose the provision of an effective puller so anchored in the substance of the stopper that it will remove the stopper from the mouth and neck of a bottle without either dismembering it or rendering it unfit for further use, or becoming separated from it.

In the accompanying drawing, Figure 1 is a diametrical vertical section of the upper part of a bottle or a jug having its stopper equipped with my improved puller. Fig. 2 is a diametrical section of a stopper with my puller inserted in it and made in such modified form as may be more adapted for large stoppers. Fig. 3 is a section about as on the line 3—3 of Fig. 1. Fig. 4 is a top view of either Fig. 1 or 2. Fig. 5 is an elevation of the puller alone in a modified form. Fig. 6 is a right hand side view of Fig. 5. Fig. 7 is a side elevation and part of an edge view of the puller further modified. Fig. 8 is a top view of a stopper with either of the modified pullers Figs. 5 and 7 applied to it.

Referring to the drawing by reference numerals, 10 designates the neck of any form and size of a bottle or a jug, which is closed by a cork or other stopper 11. The improved pulling device is formed of a single piece of metal and comprises a bar 12 adapted to bear upon the top of the stopper and is provided at its middle with a catch 13, by which to pull the stopper; said catch may be the shape of a ring large enough for the insertion of a finger, and may be soft enough to be bent over upon the stopper during boxing and storing or shipping of the bottles, as indicated in dotted lines to the right in Fig. 3, or the catch may be as small as indicated at 13^x in Figs. 5 to 8, in which event the catch serves merely as an engaging point for a nail, spike, shoe-hook or other suitable means for extracting the stopper.

The pulling device further consists of one or more sharp prongs 14, which extend downwardly from the bar 12 and are each

provided with a pair of anchoring wings 15, 55 except in the modification Fig. 7, where only one wing, 15^a, is employed. The wings are connected with the prongs by the short and relatively narrow necks, 18. Such separation of the wings from the prongs as is secured 60 by the interposition of these necks and the relatively narrowing of the metal portion conduces to flexibility, essential in the setting of the wings in the substance of the stopper, when upward pull force is applied. 65

Each wing is resilient and has a normal tendency to stand at an incline, as shown in nearly all the views; and each wing has its end directed upwardly and formed with square or blunt shoulders 16, by which to engage and lift the stopper. To insure said engagement each wing is also provided with an inclined sharp point or barb 17, said points being inclined outward beyond the plane of the wing, 16, as shown to the right 75 in Fig. 7. The incline is very little, and only enough for the purpose in view.

In the operation or use of the device, the prong or prongs 14, having sharp exterior edges, are forced down into the stopper until the bar 12 bears upon the latter. The resilient force of the metal of which the puller is formed causes the points of the barbs to trench their ways, as the prong descends, and embeds the sharp ends of the 85 barbs in the substance of the stopper, whereby they assume a suitable position for penetrating the stopper interiorly and at an angle outwardly. When the stopper is to be extracted from the bottle a pull upward at 90 the catch 13, or 13^x, will cause the prong or prongs to move slightly upward in the stopper and by such movement make the wings engage firmly in the stopper, especially as the barbs 17 aid the wings in resuming their 95 normally inclined position, from which they were forced by being driven with the prong down into the stopper. After such slight retroactive movement of the prong, or prongs, the wings are thus firmly engaged 100 with the stopper, and the latter is extracted by the last and greatest part of the pulling action. The stopper and its puller or extracting device may be used over and over again. And in Fig. 7 is shown how the 105 wing 15^a may be struck out in the prong and bent over toward one side of it.

To fully understand the nature of the in-

vention it is necessary to keep in mind that the difficult problem of this class of art has not been to find means of introducing a wire or stem carrying barbs into the stopper after the insertion of the latter in place but to find a puller which could be introduced and that when introduced was capable of drawing out the stopper without tearing it into two portions, leaving one in the bottle neck.

10 This invention solves that problem.

Inasmuch as nearly all stoppers have been heretofore and will presumably continue to be made of cork, this device has been adapted to the characteristics of cork. 15 The shoulders are sufficiently diminutive and acute for indentation, and sufficiently dull, or blunt, to cause the impacting of the substance in all directions rather than a severance. If the latter resulted, dismemberment of the stopper would ensue, but an indenting and impacting results in the integral upward movement of the stopper upon the application of adequate final pull force.

25 In Figs. 5 to 8 is shown how the puller may be stamped most economically in the form of a straight strip of sheet metal and bent toward one of its flat sides into the desired shape, while in Figs. 1, 2 and 3 is 30 shown how the complete puller may be stamped out of sheet metal in a single operation, even the wings 15 may be pressed into the inclined position in the same one operation, or they may be inclined by a second 35 operation. The several forms shown are mainly for selection in manufacturing the article for use on large, medium, and small stoppers.

Many changes of construction and arrangement may be made in the device as 40 above explained, without departing from my present invention, and I do not limit myself to the details and modifications herein shown and described.

45 Having thus fully described the preferred, as well as the modified form of the invention, I claim as follows:

1. A puller for closures comprising a metal prong sharply pointed at one end 50 having also sharpened exterior edges adjacent to the point, wings on laterally extended portions of the prong, the wings bluntly shouldered on each side of a sharp point formed centrally thereon, and slanted 55 at an angle from the plane of the wing.

2. A puller for closures comprising a metal prong sharply pointed at one end having also sharpened exterior edges adjacent to the point, wings on laterally extended 60 portions of the prong, the wings bluntly shouldered on each side of a sharp point formed centrally thereon, and slanted at an angle from the plane of the wing; each wing slanted at an angle from the plane of the 65 prong.

3. A puller for closures comprising a metal prong sharply pointed at one end having also sharpened exterior edges adjacent to the point, wings on laterally extended portions of the prong, the wings bluntly shouldered on each side of a sharp point formed centrally thereon, and slanted at an angle from the plane of the wing, each wing slanted at an angle from the plane of the prong, and a short and relatively narrow 75 neck connecting each wing with the prong, below space made by cutting out a narrow strip of the metal in forming the prong of the puller, to secure adequate flexibility of parts in the act of setting the wings in the 80 substance of the stopper.

4. In combination with a stopper, a puller comprising a flat metal prong embedded in the stopper and projected downwardly, the prong having wings formed on lateral projections thereof, the wings slanted from the vertical line of the prong, each wing having a sharp upwardly projected central portion and a relatively blunt shoulder on each side thereof.

5. In combination with a stopper, a puller comprising a flat metal prong embedded in the stopper and projected downwardly, the prong having wings formed on lateral projections thereof, the wings slanted from the vertical line of the prong, each wing having a sharp upwardly projected central portion and a relatively blunt shoulder on each side thereof, the prong being centrally apertured above a bar formed in its upper terminal for 100 convenience in use.

6. A puller for closures comprising a metal prong sharply pointed at one end having also sharpened exterior edges adjacent to said point, wings on laterally extended portions of the prong, the wings bluntly shouldered on each side of a sharp point formed centrally thereon, and slanted at an angle from the plane of the wing, and a plurality of such devices joined together 105 by a centrally apertured bar resting on the stopper, all the prongs anchored in the stopper as described.

7. A puller for closures comprising a metal prong sharply pointed at one end 115 having also sharpened exterior edges adjacent to the point, wings on laterally extended portions of the prong, the wings bluntly shouldered on each side of a sharp point formed centrally thereon, and slanted at an 120 angle from the plane of the wing, each wing slanted at an angle from the plane of the prong, and a plurality of such devices joined together by a centrally apertured bar resting on the stopper, all the wings anchored 125 in the stopper as described.

8. In a combination of a stopper and puller, a single sharply pointed and bluntly shouldered member formed on the prong of the puller.

9. In a combination of a stopper and puller, a single sharply pointed and bluntly shouldered member formed on the prong of the puller, the sharply pointed portion inclined upwardly at an angle with respect to the plane of the member below the shoulders.

In testimony whereof I affix my signature in presence of two witnesses.

THOMAS C. SPELLING.
